UNITED STATES PATENT OFFICE.

WILLIAM I. CRUM, OF WICHITA, KANSAS.

DESIGN FOR A CAP.

58,306.

Specification for Design. Patented July 12, 1921.

Application filed December 30, 1920. Serial No. 434,161. Term of patent 14 years.

To all whom it may concern:

Be it known that I, WILLIAM I. CRUM, a citizen of the United States of America, residing at Wichita, in the county of Sedgwick and State of Kansas, have invented a new, original, and ornamental Design for a Cap, of which the following is a specification, reference being had to the accompanying drawing, forming part thereof.

In the drawing:

Figure 1 is a side elevation of a cap showing my new design;

Fig. 2 is a top plan view of the same;

Fig. 3 is an end elevation of the same.

I claim:

The ornamental design for a cap, as shown.

WILLIAM I. CRUM. [L. S.]
